(57) **CLAIM**

The ornamental design for a fork lift truck, as shown and described.

DESCRIPTION

FIG. 1 is a perspective view of the fork lift truck;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the fork lift truck as seen from the top, front and left sides showing our new design and its environment.

The broken lines shown in the figures are for the purpose of illustrating environment and form no part of the claimed design.
